Primary Examiner—Joel Sincavage

[57] CLAIM

The ornamental design for an interface cable, as shown and described.

DESCRIPTION

FIG. 1 is a front perspective view showing my new design of an interface cable, and prior to its connection to an illustrative smart card reader, which is indicated in dashed lines and forms no part of the claimed invention;

FIG. 2 is a front perspective view of the design shown in FIG. 1, and connected to the illustrative smart card reader; FIG. 3 is a rear perspective view of the design shown in FIG. 1, and prior to its connection to the illustrative smart card reader; and,

FIG. 4 is a rear perspective view of the design shown in Fig. 1, and connected to the illustrative smart card reader.
